US00D796750S

(12) United States Design Patent (10) Patent No.: US D796,750 S
Hederstierna et al. (45) Date of Patent: * Sep. 5, 2017

(54) DISHWASHER RACK

(71) Applicant: Electrolux Appliances Aktiebolag,
Stockholm (SE)

(72) Inventors: Rickard Hederstierna, Hågersten (SE);
Pontus Kåberg, Sollentuna (SE);
Adam Szczepanowski, Stockholm (SE);
Daniel Mesa, Stockholm (SE)

(73) Assignee: Electrolux Appliances Aktiebolag,
Stockholm (SE)

() Term: 14 Years

(21) Appl. No.: 29/480,932

(22) Filed: Jan. 30, 2014

(30) Foreign Application Priority Data

Aug. 1, 2013 (EM) 002285155

(51) LOC (10) Cl. 15-05

(57) CLAIM

The ornamental design for a dishwasher rack, as shown and described.

DESCRIPTION

FIG. 1 is a perspective view of a dishwasher rack showing our new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a left side elevation view thereof; and,

FIG. 7 is a right side elevation view thereof.

Broken lines are directed to unclaimed features. The broken lines form no part of the claimed, design.

1 Claim, 6 Drawing Sheets
